H. M. BRAYTON

COMBINATION FUSE

Filed Aug. 11, 1924

UNITED STATES PATENT OFFICE.

HAROLD M. BRAYTON, OF DOVER, NEW JERSEY.

COMBINATION FUSE.

Application filed August 11, 1924. Serial No. 731,468.

(GRANTED UNDER THE PROVISIONS OF THE ACT OF MARCH 3, 1883, 22 STAT. L., 625.)

The invention described herein may be used by the Government, or any of its officers or employees in prosecution of work for the Government, or by any other person in the 5 United States, without payment to me of any royalty thereon, in accordance with the act of March 3, 1883.

The subject of this invention is a combination fuse.

10 In fuses of the type which have a movable projecting striker mounted in the nose of the fuse, there is present a constant source of danger of the striker being moved rearwardly to initiate explosion during handling 15 of the projectile and while it is in the bore of the gun.

The object of the present invention is to provide a striker which may be selectively set to be held against rearward movement 20 at all times or immovable only until the projectile attains a predetermined rotational velocity in flight. The safety device is so arranged that setting of the fuse from delay to instantaneous action is accomplished by 25 the simple operation of removing a cotter pin.

The functioning of the instantaneous or delay elements are entirely independent of each other so that instantaneous action may 30 occur without interfering with or preventing delay action. This construction permits the delay element to function in the event of misfire of the instantaneous element, or failure to fire as in low angle impact where the 35 striker does not encounter a resistance.

To these and other ends, my invention consists in the construction, arrangement, and combination of elements, described herein-after and pointed out in the claims forming 40 a part of this specification.

A practical embodiment of my invention is illustrated in the accompanying drawings, in which,

Fig. 1 is a longitudinal sectional view of 45 my improved fuse, the parts shown being set for delay action and in unarmed position;

Fig. 2 is a similar view taken on the line 2-2 of Fig. 1; and

Fig. 3 is a sectional view taken on the line 3-3 of Fig. 1.

Referring to the drawings by numerals of reference:

In carrying out my invention, I provide 55 a suitable container comprising a fuse head

10, which is in threaded engagement with a fuse body 11. The nose of the fuse head is elongated and bored to form a casing, in which is slidably mounted a striker consisting of a striker head 12, terminating within 60 the fuse in a flanged portion 13, a rod 14, and a firing pin 15. The striker may be held in its forward position against air pressure during flight by means of a coil spring 16, which surrounds the rod 14 and 65 is confined between the flange 13 and the rear end of the casing.

The fuse head 10 is formed at its rear end with a cavity 17 into which projects a stationary firing pin 18, suitably secured in 70 the head specifically by a threaded shank 19 and held by a pin 20. Within the cavity 17 is mounted a plunger 21, which is free to move longitudinally, but is constrained against rotary movement with respect to the 75 head by a pin 22 fixed to the head and projecting into a groove extending the length of the plunger.

The plunger is normally retained on its seat at the rear end of the cavity 17 by a 80 spring 23, which is confined between the plunger and the head 10, and which may be of sufficient strength to withstand all shocks incidental to handling, or, if desired, the usually centrifugally released safety pins may 85 be employed to hold the plunger safe. An aperture 24 is formed axially of the plunger, through which the firing pin 15 is adapted to pass and a second aperture is formed off center for the reception of a primer detonator 25, the flash from which may pass through a duct 26 which opens at the rear face of the plunger.

A disc 27 interposed between the head and the body is centrally apertured to permit passage therethrough of the firing pin 15 and the flash from the primer detonator 25. The disc 27 carries a primer detonator 28 for transmitting ignition to a booster charge 29, disposed in the base of the body 11.

The fuse head 10 is formed with a transverse passage 30 forwardly of the cavity 17 for the reception of a cylindrical bolt 31, which is bifurcated at one end to straddle the firing pin 15 and also formed with a flattened upper surface 32 to ride under the rod 14, whereby the firing pin will be held against rearward movement towards the primer and the bolt in turn will be held against rotation. The rod 14 and firing pin 110

15 will also serve to limit the inward position of the bolt to align a circumferential groove 33 on the bolt with an aperture passing transversely through the fuse head at right angles to the bolt and through which a cotter pin 34 may be inserted to securely hold the bolt in safe position. A spring 35, confined between the bolt and a screw plug 36 is provided for normally holding the bolt in safe position when the cotter pin is withdrawn and the fuse accordingly set for instantaneous action.

The fuse is issued with the cotter pin engaging the bolt and to secure delay action on impact no setting operation will be necessary. When a projectile equipped with this fuse is fired, the inertia force created on linear acceleration of the projectile in the bore of the gun will have no effect on the 20 striker as the bolt positively prevents its rearward movement. The cotter pin 34 prevents the bolt from moving outward through the action of centrifugal force during rotational flight of the projectile and the firing 25 pin 15 will consequently be prevented from functioning on impact. Ignition is free to take place, however, as the plunger 21 impelled forward on impact through inertia will cause the stationary firing pin 18 to 30 prime the primer detonator 25.

The fuse is set for instantaneous action by merely withdrawing the cotter pin 34 when the spring 35 will normally hold the bolt in safe position to prevent rearward movement 35 of the striker. When fired, linear acceleration while in the bore of the gun being greatly in excess of centrifugal force will cause the striker to setback with great pressure on its support thereby effectually holding the bolt against lateral movement. When the projectile leaves the gun, the linear acceleration ceases and the bolt will be 40 free to release the striker through the action of centrifugal force when the projectile attains arming speed. The striker will be retained in armed position during flight by the spring 16 and on impact it will be free to be moved rearwardly to prime the primer detonator 28. However, in the event of misfire or failure to fire the plunger will not 45 be deterred from moving forward to function the delay element of the fuse.

It will be readily understood that the instantaneous striker may be mounted by itself 55 in a fuse, the bolt serving as a safety device to prevent arming of the striker until the projectile is in flight and the locking pin serving as an additional precautionary measure during storage and transportation.

60 While in the foregoing there has been illustrated and described such combination and arrangement of elements as constitute the preferred embodiment of my invention, it is nevertheless desired to emphasize the 65 fact that interpretation of the invention

should only be conclusive when made in the light of the subjoined claims.

I claim:

1. A combination instantaneous and delay fuse including a movable striker, a centrifugally releasable bolt mounted transversely of the fuse and formed with a bifurcated end for straddling the striker, said bolt further formed with a circumferential groove, a removable pin passing through the 75 fuse and engaging in the groove for selectively rendering the striker either operative or inoperative, and an auxiliary delay firing mechanism mounted to ignite a common charge independently of the striker. 80

2. A combination instantaneous and delay fuse including a movable striker, a centrifugally releasable bolt mounted transversely of the fuse and formed with a flattened upper surface adapted to ride under a shoulder of the striker, said bolt further formed with a circumferential groove, a removable pin passing through the fuse and engaging in the groove for selectively rendering the striker operative or inoperative, and an auxiliary delay firing mechanism mounted to 85 ignite a common charge independently of the striker. 90

3. A combination instantaneous and delay fuse including a movable striker, a bolt mounted transversely of the fuse and adapted to hold the striker against movement while in turn being held against rotational movement, said bolt formed with a circumferential groove, means for releasably holding the bolt in contact with the striker, a removable pin passing through the fuse and engaging in the groove for selectively rendering the striker operative or inoperative, and an auxiliary delay firing mechanism mounted to 100 ignite a common charge independently of the striker. 105

4. A combination instantaneous and delay fuse including a movable striker, a bolt mounted transversely of the fuse and engageable with the striker to prevent movement thereof, means for releasably holding the bolt in safe position, means engaging the bolt, and removable from the fuse for selectively rendering the striker operative or 110 inoperative, and an auxiliary delay firing mechanism mounted to ignite a common charge 115 independently of the striker.

5. A combination instantaneous and delay fuse including a movable striker, a bolt 120 mounted transversely of the fuse and engageable with the striker to prevent movement thereof, means for releasably holding the bolt in safe position, means removable from the fuse for selectively rendering the striker operative or inoperative, and an auxiliary delay firing mechanism mounted to 125 ignite a common charge independently of the striker.

6. A combination instantaneous and delay 130

fuse including a movable striker, a bolt mounted transversely of the fuse and engageable with the striker to prevent movement thereof, means for releasably holding the bolt in safe position, means for selectively rendering the striker operative or inoperative, and an auxiliary delay firing mechanism mounted to ignite a common charge independently of the striker.

5 10 7. A combination instantaneous and delay fuse including a movable striker, normally releasable means for preventing movement of the striker, means assembled to the fuse for rendering the striker inoperative on impact, said means being removable for ren-

dering the striker operative, and an auxiliary delay firing mechanism mounted to ignite a common charge independently of the striker.

8. A point detonating fuse including a body, a movable striker, a centrifugally releasable cylindrical bolt mounted transversely in the body and formed with a bifurcated end and a flattened upper surface for engaging the striker, said bolt further formed with an annular groove, a spring for holding the bolt in engagement with the striker and a removable locking pin insertable through the fuse body and engageable in the annular groove of the bolt.

20 25 HAROLD M. BRAYTON.
